UNITED STATES PATENT OFFICE.

SIDMOOR S. SAGER, OF BUFFALO, NEW YORK.

FRUIT JAR.

Application filed May 20, 1924. Serial No. 714,579.

To all whom it may concern:

Be it known that I, SIDMOOR SAMUEL SAGER, a citizen of the Dominion of Canada, a resident of the city of Buffalo, in the county of Erie, in the State of New York, in the United States of America, have invented certain new and useful Improvements in Fruit Jars, of which the following is the specification.

10 My invention relates to improvements in fruit jars, and the object of the invention is to provide a suitable container of the vacuum type for fruit, vegetables and the like, wherein a pump for exhausting the air 15 therefor can be used in conjunction therewith.

A further object is to devise a jar in which air can be readily admitted when it is desired to open the sealed jar.

20 A still further object is to devise a jar which will be simple in construction, and which can thus be readily manufactured.

With these and other objects in view, my invention consists of a jar constructed and arranged all as hereinafter more particularly described and illustrated in the accompanying drawing in which:

Fig. 1 is a vertical section through a jar, constructed according to my invention, 30 showing the cover thereon and the pump applied to the jar.

Fig. 2 is a plan view of the jar with the cover removed, and

Fig. 3 is a vertical section of the upper 35 portion of a modified form of jar.

Like characters of reference indicate corresponding parts in the different views.

1 is the jar or container body which may be constructed of any suitable material. 40 2 is a single annular upwardly extending flange at the top of the jar, said flange being interrupted at one or more points to constitute an aperture or notch 3. 4 is a substantially horizontally extending annular surface upon which the washer or seal-

45 ring 5 is designed to rest. 6 is the jar cover having the depending annular flange 7 with a lower edge 8 of preferably V-shape in cross section which is designed to co-act with the ring 5 when the jar is sealed. 9 is a second substantially horizontally extending annular surface in the vicinity of the top of the jar adapted to act as a seat for the ring 10 of the pump which is 55 designed to rest thereon when the jar is being sealed.

The pump forms no part of the present invention, being shown merely to give a clear idea of the several parts of the container.

In the form of the jar shown in Figures 1 and 2 it will be noted that the flange 2 is positioned at the inside of the lip, and that the ring 5 is prevented from inward distortion, being in contact therewith, whereas 60 in the modification illustrated in Figure 3 the flange 2 is deposited intermediately of the width of the lip. In the latter case the flange prevents outward distortion of the sealing ring 5 when such ring is compressed. 65 In either case the flange 2 prevents the ring 5 being displaced during the sealing operation.

In the form of jar illustrated in Figures 1 and 2 the surface 9 constituting the seat for 75 the pump ring 10 is positioned below the plane of the surface 4, and thus an annular shoulder 11 is formed which co-acts with the inner surface of such ring 10, preventing its distortion during the pumping operation. 80 In the modification the inner surface of the ring 10 is in engagement with the outer surface of the flange 2 when the pump is applied to the jar for exhausting the air therefrom.

In opening the sealed jar a pin or other sharp instrument is inserted under the sealing ring 5 into the container 1, thus allowing air to be admitted to such container, when the cover 6 can be removed. In the 90 form of jar illustrated in Figures 1 and 2 the pin is first inserted under the ring 5, and then through the notch or aperture 3, whereas in modified form the pin is inserted through the exposed notch 3 and then under the ring 5.

In either case the same result is produced.

In order to make more comprehensive the uses of the various parts of my jar I will now describe the method of sealing the 100 same.

The jar container is first filled with the desired material, the sealing ring being placed in position on the seat 4. The cover is then put in place so that the V-shaped lower edge of 8 of the flange 7 co-acts with the upper surface of the sealing ring 5. The pump, which may be of any suitable construction, but preferably that disclosed in my Canadian Patent Number 220,402 105 issued July 4, 1922, is now applied to the container so that the ring 10 seats on the 110

annular surface 9. The pump is now operated to exhaust the air, and during the suction stroke the cover 6 of the jar is caused to be raised sufficiently to permit the escape 5 of air from the container. On the down stroke the cover 6 is drawn down against the sealing ring 5 due to the rarefied condition of the air within the jar, thus preventing the replacement of air exhausted from within 10 in the container. The pump is operated until the required vacuum is obtained in the jar, when it is removed therefrom.

From the above description it will be seen that I have devised a simple and effective 15 jar, particularly for use where it is desired to remove the air from the jar, and it is moreover an improvement on the jar covered by my Canadian Patent Number 205,096 in that the two concentric flanges described in 20 such specification are replaced by a single annular flange, thus effecting a considera-

ble improvement in construction. Likewise in my present form of jar the outer wall of the container is of substantially uniform diameter throughout its length, thus making for a jar of pleasing appearance. 25

What I claim as my invention is:

A container of the class described comprising a body portion having an annular surface constituting a sealing ring seat, a sealing ring seated on the annular surface constituting its seat, and a cover having a depending annular flange adapted to co-act with the sealing ring, the body having a shoulder constituting a pump seat below the sealing ring seat and outside the exterior periphery of the cover, whereby a pump may be applied to said jar for exhausting the air therefrom. 30

In testimony whereof, I affix my signature. 40

SIDMOOR S. SAGER
